E. KILLEBREW.

HEADLIGHT DIMMER.

APPLICATION FILED JAN. 30, 1917.

1,238,685.

Patented Aug. 28, 1917.

UNITED STATES PATENT OFFICE.

EDWARD KILLEBREW, OF ST. LOUIS, MISSOURI.

HEADLIGHT-DIMMER.

1,238,685.

Specification of Letters Patent. Patented Aug. 28, 1917.

Application filed January 30, 1917. Serial No. 145,455

To all whom it may concern:

Be it known that I, EDWARD KILLEBREW, a citizen of the United States, residing at St. Louis, in the State of Missouri, have invented new and useful Improvements in Headlight-Dimmers, of which the following is a specification.

This invention relates to headlight dimmers, being especially designed for the headlamps of automobiles in order to enable drivers to comply with traffic regulations in congested districts by restricting the illumination of the roadway and avoiding the projection of straight ahead or upwardly extending rays of light which prove dazzling and are therefore dangerous to traffic in general.

One of the chief objects of the present invention is to provide a dimmer which may be easily applied to any headlamp by merely inserting the same in place therein, the dimmer being easily removable when the operator of a machine arrives in the open country where the traffic restrictions do not apply and where he needs the full light from the headlamps.

With the above and other objects in view, the invention consists in the novel construction, combination and arrangement of parts, as herein described, illustrated and claimed.

30 In the accompanying drawings:

Figure 1 is a vertical fore and aft section through a headlamp showing the dimmer of this invention in its applied relation therein.

Fig. 2 is a rear elevation of the dimmer.

35 Fig. 3 is a front elevation of the dimmer.

Fig. 4 is a fragmentary sectional view showing one of the retaining devices for the dimmer.

Fig. 5 is a sectional view similar to Fig. 1 showing the dimmer applied to a headlamp of another type.

Fig. 6 is a rear elevation of the dimmer shown in Fig. 5.

Referring to the drawings A generally designates a headlamp of any ordinary or preferred construction, the same being shown as provided with the usual front glass, lens or panel 1 and containing a Presto-lite burner 2 or an electric lamp 3 50 or both as may be preferred.

The dimmer contemplated in this invention comprises a disk-shaped body 4 preferably of sheet metal, formed with a central aperture 5 and also provided at one side of the aperture 5 with a socket 6 of tubular

8 by which said socket is secured to the body 4 by suitable fastening means.

The body 4 of the dimmer is held securely in place by means of a circular series of arcuate springs 9 secured to the marginal portion of the body 4 so as to bear against the inner surface of the body of the lamp A for the purpose of retaining the body 4 in a certain fixed relation therein and permitting the dimmer to be removed from the lamp A when not needed.

Extending through the aperture 5 of the body 1 is a top ray interceptor 10 having an attaching flange 11 and a downwardly turned marginal portion or flange 12 the area of which is sufficient to obstruct, deflect or intercept the necessary number of rays of light to prevent the blinding of pedestrians or the drivers of other vehicles. A similar but smaller bottom ray interceptor 13 extends forwardly from the flange 11 to prevent the downwardly projected rays of light from the lamp or burner striking against the bottom of the reflector and thereby being projected upwardly.

On its rear side the body 4 of the dimmer is provided with a rearwardly projecting spring clasp 14 adapted to embrace the acetylene or Presto-lite burner 2. An electric lamp embracing loop 15 is also arranged in rear of the body 4 of the dimmer and connected thereto by a spring shank 16. The spring shank 16 above referred to is inserted through the socket 6 and held adjusted by the screw 7. The devices 14 and 15 thus provide additional retaining means for the body of the dimmer. By opening or removing the front panel 1 of the lamp A, the dimmer hereinabove described may be readily inserted and removed as found necessary.

Having thus described my invention, I claim:

1. A dimmer of the class referred to comprising a disk-shaped body having a central aperture therein, a top interceptor extending forwardly from said body at the upper side of said aperture, a bottom interceptor extending forwardly from said body in line with the lower margin of said aperture, and resilient means for holding said body in position in a lamp case.

2. A dimmer of the class referred to comprising a disk-shaped body having a central aperture therein, a top interceptor extending forwardly from said body at the upper side of said aperture, a bottom interceptor

extending forwardly from said body in line with the lower margin of said aperture, and resilient means for holding said body in position in a lamp case, said means embodying 5 a circular series of springs secured to the marginal portion of the body and adapted to bear at their opposite extremities against the inside wall of the lamp case.

3. A dimmer of the class referred to comprising a disk-shaped body having a central aperture therein, a top interceptor extending forwardly from said body at the upper side

of said aperture, a bottom interceptor extending forwardly from said body in line with the lower margin of said aperture, and 15 resilient means for holding said body in position in a lamp case, said means comprising a loop-shaped burner-embracing device.

In testimony whereof I affix my signature in presence of two witnesses.

EDW. KILLEBREW.
